UNITED STATES PATENT OFFICE.

JACQUES GÉRIN, OF PARIS, FRANCE.

DESIGN FOR A BODY CARRIAGE FOR MOTOR CARS.

Application filed August 31, 1925, Serial No. 14,670, and in France April 22, 1925. Term of patent 7 years.

To all whom it may concern:

Be it known that I, JACQUES GÉRIN, a citizen of the Republic of France, residing at Paris, France, have invented a new, original, and ornamental Design for Body Carriage for Motor Cars, of which the following is a specification, reference being had to the accompanying drawing, forming part thereof.

In the drawing:

Fig. 1 is a side elevational view of the

body carriage for motor cars showing my new design,

Fig. 2 is a top plan view thereof,

Fig. 3 is a front elevational view, and

Fig. 4 is a rear elevational view thereof.

I claim:

The ornamental design for a body carriage for motor cars, substantially as shown.

In testimony whereof I have signed my name to this specification.

JACQUES GÉRIN.
